UNITED STATES PATENT OFFICE

160,246

EAR ORNAMENT

Guisepppe Brandano, Lawrence, Mass., assignor of one-half to Louis Bell, Boston, Mass.

Application November 30, 1949, Serial No. 6,345

Term of patent 14 years

(Cl. D45—9)

To all whom it may concern:

Be it known that I, Guisepppe Brandano, a citizen of the United States, residing at Lawrence, in the county of Essex and Commonwealth of Massachusetts, have invented a new, original, and ornamental Design for an Ear Ornament, of which the following is a specification, reference being had to the accompanying drawing, forming part thereof.

Fig. 1 is a front elevational view of an ear ornament embodying my new design, and

Fig. 2 is a side elevational view thereof.

I claim:

The ornamental design for an ear ornament, as shown.

GUISEPPE BRANDANO.
